UNITED STATES PATENT OFFICE.

HORACE CHESTERTON MARTIN, OF MIDDLESBORO, KENTUCKY.

WOVEN STRAP FOR SUSPENDERS.

Application filed April 19, 1926. Serial No. 103,012.

This invention relates generally to new and useful improvements in woven strap for suspenders although from certain aspects it relates to new and useful improvements in woven fabrics.

Heretofore, overall suspenders have been formed on a sewing machine from two strips of woven fabrics of relatively different colors and of relatively different widths. 10 The manufacturing of these suspenders have been quite costly for the following reasons:—Two body fabrics, generally blue and white, must be carried in stock, cut into strips, and the strips formed into the suspenders. When forming each strap of a pair of suspenders, a blue strip is superposed on a white strip, the former being wider than the latter, and these strips are fed by an operator through a folder and 20 thence passed to the stitching mechanism of a multiple needle sewing machine, the marginal longitudinal portions of the blue front strip being thereby folded under the edges of the white strip and secured thereto by lines of straight-a-way stitches formed by the sewing machine. The needle threads employed in the sewing machine are usually white in color and consequently the stitches form a resultant ornamental appearance on 25 the front or outer face of the strap.

One of the important objects of my invention is to provide a one-piece suspender strap which is constructed to simulate a two-piece sewing machine made suspender strap.

Another important object of my invention is to form a suspender strap of woven fabric in which one or more of the warp threads extending longitudinally thereof is 40 of a color different from the general color of the strap for simulating one or more lines of straight-a-way stitches.

A further object is to provide a woven flat tube suspender strap in which the color of the front face contrasts with the color of the rear face and extends along opposite marginal portions of the rear face for simulating a sewing machine made two-piece suspender strap.

50 A still further object of my invention is to construct a woven fabric in which one of the inherent threads is of a color different from the general color of the fabric for simulating a line of straight-a-way stitches formed in the fabric.

With these and other objects in view

which will more fully appear and the nature of the invention will be more clearly understood by following the description, the appended claims, and the several views illustrated in the accompanying drawings, in which—

Fig. 1 is a plan view of a pair of suspenders constructed in accordance with my invention,

Fig. 2 is a rear view of one of the supporting straps,

Fig. 3 is an enlarged transverse sectional view of the tubes forming one of the supporting straps, and

Fig. 4 is an enlarged detail plan view showing a portion of the front face of the tube.

Referring to the accompanying drawings, it will be seen that I have embodied my invention in a pair of suspenders A which includes a pair of suspender straps B—B, as shown in Fig. 1. In this form of suspender each strap includes an elastic portion C which is formed from a pair of 75 elastic web sections 5—5 arranged side by side. The elastic sections of one suspender strap are interlaced with the elastic sections of the other suspender strap. The opposite end portions of each suspender strap are 80 each formed from a woven tube 6. In Fig. 1 the woven fabric forming the tube 6 is more or less diagrammatically illustrated, the details thereof being better shown in Figs. 3 and 4.

Each fabric tube 6 is formed from a plurality of warp threads which extend longitudinally of the tube and a plurality of weft threads which extend transversely of the tube. In practice only a single weft thread 95 is employed and this thread extends in spiral formation throughout the length of the tube, the effect being to form a plurality of transversely extending weft threads. The tube is pressed to form a flat tube having front and rear faces 7 and 8 respectively. The threads forming the front face 7 of the tube are colored to form substantially a solid dark color in order to contrast with the white color of the rear face 8. Usually blue is employed in coloring the front face 7, although it will be understood that any other color which contrasts with the color of the rear face 8 may be employed. The color of the front face extends along opposite marginal portions 9—9 of the rear face so as to give the appearance

of a suspender strap formed from two separate pieces of material.

In order to further simulate a two-piece sewing machine made strap, I have employed 5 one or more white warp threads in the front face 7 of the woven fabric and these threads are so woven as to produce in effect one or more lines of straight-a-way stitches which extend parallel to and are located adjacent 10 the longitudinal edges of the strap. While I have shown a plurality of lines of these simulated stitches, it will of course be understood that I may employ only one line thereof or any combination or arrangement 15 of such lines of simulated stitches.

In Figs. 3 and 4, which illustrate the particular weave employed, the blue warp threads are indicated by the numeral 10, the white warp threads employed in the 20 front face 7 for simulating the stitches are indicated by the numeral 11, and the weft threads are indicated by the numeral 12. The consecutive warp threads progressively and alternately pass over a plurality of weft threads and under a lesser number of said weft threads. In the drawings, I have shown the warp threads as passing over two weft threads and thence under one weft 25 thread. By this arrangement each white warp thread 11 forms a resultant line of simulated straight-a-way stitches, each stitch being indicated by the numeral 13. By means of the weaving described above, it will be apparent that by providing an even 30 number of blue warp threads 10 intermediate adjacent white warp threads 11, the resultant simulated straight-a-way stitches formed by the respective white warp threads will be disposed in successive parallel relation and thereby simulate a plurality of lines of 35 stitches made by a sewing machine employing three needles abreast.

From the foregoing, it will be observed 40 that I have provided a woven body fabric in which one of the inherent warp threads is of a color different from that of the other warp threads for simulating a line of 45 straight-a-way stitches formed in said fabric; that I have provided a supporter strap 50 for suspenders which is formed of a one-piece flat tube of woven fabric constructed to simulate a two-piece sewing machine made strap, and that the color of the front face 55 of the tube contrasts with the color of the rear face of the tube and extends along opposite marginal portions of said rear face.

It is of course to be understood that the

details of structure and arrangements of parts may be variously changed and modified without departing from the spirit and 60 scope of my invention.

I claim:

1. A strap comprising a flat woven fabric constructed to simulate a sewing machine made strap, said strap having front and 65 rear faces, the color of the front face contrasting with the color of the rear face, certain of the inherent warp threads adjacent the respective longitudinal edges of the strap being of a color different from the 70 general color of the face for simulating lines of straight-a-way stitches formed in said fabric.

2. In a suspender, a supporting strap comprising a one-piece flat tube of woven fabric 75 constructed to simulate a two-piece sewing machine made strap, said tube having front and rear faces, the color of the front face contrasting with the color of the rear face, one of the inherent warp threads of the 80 front face adjacent one longitudinal edge thereof being of a color different from the general color of the front face for simulating a line of straight-a-way stitches 85 formed in said fabric.

3. In a suspender, a supporting strap comprising a one-piece flat tube of woven fabric constructed to simulate a two-piece sewing machine made strap, said tube having front and rear faces, the color of the front face 90 contrasting with the color of the rear face, certain of the inherent warp threads adjacent the respective longitudinal edges thereof being of a color different from the general color of the face for simulating lines 95 of straight-a-way stitches formed in said fabric.

4. In a suspender, a supporting strap comprising a one-piece flat tube of woven fabric 100 construed to simulate a two-piece sewing machine made strap, said tube having front and rear faces, the color of the front face contrasting with the color of the rear face and extending along opposite marginal portions 105 of the rear face, certain of the inherent warp threads adjacent the respective longitudinal edges thereof being of a color different from the general color of the face for simulating lines of straight-a-way 110 stitches formed in said fabric.

In testimony whereof I hereunto affix my signature.

HORACE CHESTERTON MARTIN.
